UNITED STATES PATENT OFFICE.

HERMAN P. PORTER, OF WASHINGTON, DISTRICT OF COLUMBIA.

PORTABLE AMPLIFIER FOR RADIO SETS.

Application filed October 28, 1924. Serial No. 746,320.

To all whom it may concern:

Be it known that I, HERMAN P. PORTER, a citizen of the United States, residing at Washington, District of Columbia, have invented certain new and useful Improvements in Portable Amplifiers for Radio Sets, of which the following is a specification.

This invention relates to a portable amplifying receiver especially designed to be utilized in connection with the well known radio crystal sets, and is particularly directed to the augmentation of sound as the latter is taken from the customary ear pieces or sonorous body, and it is adapted to be used in connection with any and all portable radio sets with which the usual ear pieces are now employed.

The prime object of the invention is to provide simple, durable, economical and thoroughly efficient portable means for so amplifying and augmenting the sound waves emanating from the ear pieces of the ordinary well known radio crystal sets that the sound will be thrown out so as to render it clearly audible in all parts of the room in which the said radio set is installed.

Another object of the invention is to provide sound amplifying means which will adapt itself to the usual portable radio sets now employed in connection with radio equipment without necessitating any changes in the construction of said sets.

Another object of the invention is to provide amplifying means including a sound amplifying chamber adapted to be so correlated and associated with an acoustical instrument which is surrounded in said chamber, that the sound is propagated from the acoustical instrument to the amplifying chamber and caused to audibly emerge from the chamber.

A further object of the invention is to furnish amplifying means which is compact, portable and readily manufactured, while possessing increased qualities and characteristics over the more expensive amplifiers.

Still further objects of the invention are to construct my novel amplifier from a suitable material, which will eliminate all me-

tallic and harsh sounds which usually emanate from acoustic instruments, and to so construct the improved amplifier that the rounded, sloping, inner smooth and curved walls thereof will augment and deflect the sound waves to the inner contracted portion thereof, and from the latter portion the augmented sound will be caused to emerge from the outer flaring portion clearly and audibly into a room with its natural and pleasing tone, thus eliminating all extraneous and unnatural sounds.

The foregoing and such other objects as may appear from the ensuing description are accomplished by the unitary means hereinafter more fully described, shown in the accompanying drawings, and more particularly pointed out in the claims appended hereto, it being understood that slight changes in the precise form, proportions and minor details of construction may be resorted to without departing from the spirit or sacrificing any of the advantages of the invention.

In the accompanying drawings forming a part of this specification it will be seen that:

Figure 1 is a side elevation of the novel unitary means embodying my invention.

Figure 2 is a central longitudinal section showing a plurality of ear pieces loosely placed therein.

Figure 3 is a side elevation of a slightly modified amplifying means.

Figure 4 is a central longitudinal section of the device shown in Fig. 3, showing a plurality of ear pieces with their wire connections loosely deposited therein.

Figure 5 is a side elevation of another modified form of amplifier, and

Figure 6 is a central longitudinal section of the means shown in Fig. 5, showing a plurality of ear pieces loosely disposed therein.

In the embodiment of my invention as illustrated, it will be seen that Figs. 1 and 2 show one form of my novel unitary structure constituting sound amplifying and augmenting means preferably formed of crystal glass comprising a rounded or cylindrical body portion 1, a rear semi-circular

solid deflecting wall 2, and a contracted gradually sloping neck portion 3 which merges into the outwardly flaring front or mouth portion 4. As is clearly shown in Fig. 2, it will be perceived that a plurality of the ear pieces 5, usually employed in connection with portable radio sets are loosely placed within the body portion of the amplifier, each pair of ear pieces being provided with the usual wire connections 6, and terminal metallic pins 7, the latter being adapted to be properly connected with any of the portable radio sets (not shown) now employed in general use. The body portion 1 is preferably connected at the central portion thereof with a hollow upright member 8, merging at its lower end into an outwardly extended hollow base and supporting member 9, the said upright member serving as a handle for the unitary structure, whereby it may be readily removed from one location to another.

An essential feature of the invention is the provision of a portable unitary device whose walls due to their peculiarly rounded and gradually sloping formation thereby eliminating all angles, shoulders, and like constructions, define a novel amplifying chamber, which when the customary acoustical receiving instruments of the ear piece type are loosely disposed within said chamber, the correlation of said instruments with the peculiarly shaped chamber and the material from which said chamber is formed operates to produce or define therewith a sound propagation medium leading to the contracted rounded and sloping neck portion from which the amplified sound emerges out of the flaring mouth portion in a clear, audible, pleasing and natural tone which is distinctly audible in all parts of the room within which the radio set is installed.

By reference to Figs. 3 and 4 of the drawings it will be observed that the modified form of device shown thereby consists of an elongated cylindrical body portion 10, having a semi-circular rear wall 11, a well defined gradually sloping and rounded contracted neck portion 12 with an outwardly and forwardly flared front portion 13, an upright member 14 centrally connected with the body portion serving as a handle and a laterally extended hollow base and supporting member 15, and within the body portion 10 thereof is loosely disposed a plurality of acoustical instruments or ear pieces 16, to which pieces the usual wires 17 are connected, each set of ear pieces being provided with the customary metallic radio set connections 18, as clearly shown in Fig. 4, while the modification such as shown in Figs. 5 and 6, comprises a spherical or globular body portion 19, a gradually and smoothly curved contracted neck portion 20, and an outwardly and forwardly flaring front or mouth por-

tion 21. To the central portion of the body 19 is connected an upright hollow member 20 forming a handle therefor, which merges at its lower end into hollow extended base member 21, constituting a support for the device, and within the body portion is suitably disposed a plurality of ear pieces 22, provided with the usual covered wire connections 23 and the radio set metallic connections 24.

It will be observed that my novel sound amplifying device serves to dispense with the necessity of holding or the clamping of the ear pieces to the head of those seeking to be entertained by the radio method, which holding or clamping is annoying and objectionable to many, while it also serves to so augment and qualify the sound that it may be distinctly heard in all parts of a room in a clear, non-metallic, unobstructed, and natural pleasing tone, thereby furnishing the desired entertainment to those in the room while they are employed in their ordinary duties or pursuits, and at the same time a high degree of amplification as well as accuracy of reproduction is obtained.

It will also be understood that the contracted neck portion of the device is sufficiently large to permit the hand to pass therethrough in order to suitably and loosely dispose a plurality of ear pieces within its chamber, and that the sound emanating therefrom is materially augmented or increased by increasing the number of ear pieces disposed therein. Further, it will be evident that the body and other portions of the portable amplifier may be suitably ornamented by etching or otherwise, thereby forming an ornamental as well as useful article for the premises.

Having thus described my invention what I claim and desire to secure by Letters Patent is:—

1. As a new article of manufacture, a sound amplifier of the character described, comprising an independent and disconnected structure formed with a horizontally positioned hollow circular body member having a solid imperforate concavo-convex rear-end deflecting wall, a smooth, empty and unobstructed circular interior surface extending throughout its length, an open front portion of sufficient area to permit the insertion of loosely placed acoustic receivers therein, said instruments being so disposed within said circular interior as to allow the sound waves to freely emanate therefrom and to cause the sound emanating from the structure to be amplified by said amplifier, and a supporting base.

2. As a new article of manufacture, a sound amplifier of the character described, comprising an independent and disconnected unitary structure, formed entirely of glass having a hollow circular body portion

formed with an imperforate solid semi-circular rear end deflecting wall, a smooth and unobstructed circular interior surface extending its entire length, an open front portion of sufficient area to permit the insertion of loosely placed acoustic receivers therein, said instruments being so disposed with re-

lation to the circular interior as to allow the sound waves to freely emanate therefrom and to cause the sound emanating from the 10 structure to be amplified by said amplifier, and a supporting member connected thereto.

HERMAN P. PORTER.
